UNITED STATES PATENT OFFICE.

ANDREW EKMAN, OF GRAND RAPIDS, MICHIGAN, ASSIGNOR TO GRAND RAPIDS BRASS COMPANY, OF GRAND RAPIDS, MICHIGAN, A CORPORATION OF MICHIGAN.

LATCH CONSTRUCTION.

Application filed June 22, 1928. Serial No. 287,359.

This invention relates to latch construction particularly suitable for use on ice boxes, refrigerator doors, cabinets and the like. The main objects of this invention are to provide an improved form of latch or bolt which can be locked with a key and which remains securely locked until a particular form of simple key is used for unlocking the same.

10 An illustrative embodiment of this invention is shown in the accompanying drawing in which:

Fig. 1 is a plan view of my improved form of latch mounted on a door and frame therefor.

15 Fig. 2 is a bottom plan view of the device showing the interior construction, parts thereof being broken away to more clearly show the arrangement.

20 Fig. 3 is an enlarged fragmentary detail partly in section showing the key inserted in the locking barrel.

Fig. 4 is a sectional view taken on the line 4—4 of Fig. 1.

25 Fig. 5 is an enlarged sectional view taken on the line 5—5 of Fig. 1.

Fig. 6 is a medial vertical sectional view of the sleeve for surrounding and retaining the barrel of the locking device in the handle.

30 In the construction shown in the drawings my improved device comprises an outer shell or casing 1 of pressed sheet metal or the like which is dome shaped in character and provided at opposite sides with lateral flanges having holes 2 punched or otherwise suitably formed therein adapted to receive screws 3 for attaching the shell to the device upon which it is used. The medial portion of the casing 1 is shaped with steeply sloping side walls which are punched or drilled in alignment for receiving and carrying a transversely disposed pin 4. The pin 4 pivotally supports the head end 5 of a handle 6, the casing 1 being suitably slotted to snugly receive said head end 5 as shown most clearly in Fig. 4 of the drawings.

45 The handle 6 is provided with an enlarged body portion 7, closely adjacent to the head 5, which has a hole 8, drilled transversely to the top plane thereof and substantially at right angles to the pin 4. The hole 8 through the head 7 is of uniform diameter until closely adjacent the lower or underside thereof at which point it is of reduced

diameter as shown most clearly in Fig. 5. The hole 8 is adapted to receive a locking barrel assembly which comprises a barrel 9 of less diameter than the hole 8 and which has the upper end thereof surrounded and retained by a sleeve 10 which has a tight frictional fit in the hole 8.

The outer end of the sleeve 10 has an inwardly turned flange 11 which fits over the marginal peripheral face of the barrel 9 for retaining the barrel therein. The lower end 65 of the barrel 9 is of reduced diameter to fit within the reduced inner end of the hole 8 and a shoulder 12 is formed at the point where the diameters of the barrel change, for resting upon the annular ledge of the 70 body portion where the diameters of the hole 8 change dimension, so as to restrain the barrel from axial movement in the body 7.

75 The upper or relatively large portion of the barrel 9 is provided with a diametrically disposed slot 13 for slidably receiving a transversely disposed locking pin 14 which is normally urged upwardly by a helical compression spring 15. The pin 14 has an axial 80 length slightly less than the diameter of the hole 8 and the opposite ends thereof protrude at each side of the barrel 9, the length of the sleeve 10 being considerably less than the depth of the relatively large portion of 85 the hole 8 so that an annular space 16 is provided in which the protruding ends of the pin 14 may move. The inner end of the sleeve 10 is provided with a pair of diametrically disposed notches for receiving the protruding ends of the pin 14 when rotated in 90 registry therewith and urged thereinto by the spring 15 for locking the barrel 9 against rotation relatively to the sleeve 10. The sleeve 10 when finally assembled in the body 95 7 is die fit or otherwise suitably secured to the body portion so as to prevent rotation relatively thereto.

The barrel 9 is also provided with a transversely disposed pin 18 rigidly mounted 100 therein at right angles to the slot 13 and in position to contact with the locking pin 14 when said locking pin is in engagement with the notches 17 of the sleeve 10.

A key 19 is provided for releasing the barrel 9 so that the same may rotate relatively to the sleeve 10. Said key is in a form of a relatively thin flat elongated strip of metal

having a head on one end thereof in the usual manner and the other end thereof is provided with an axially disposed notch 20 which is adapted to slidably fit over the pin 5 18 when the key is inserted in the slot 13 of the barrel 9. The slot 20 is of sufficient length to permit sufficient axial movement of the key after the end has contacted with the locking pin 14, to shift the locking pin 10 14 out of its notches 17, so that the barrel 9 may be rotated.

The inwardly disposed annular flange 11 on the outer end of the sleeve 10 is provided with a pair of diametrically disposed slots 15 for allowing the insertion of the key 19, and a pair of notches 21 are formed in opposite sides of the key and positioned so that when the key is inserted a sufficient distance to remove the locking pin 14 from its retaining 20 notches 17, the notches 21 will be in registry with the inwardly turned annular flange 11, thereby permitting the key to be rotated relatively to the sleeve 10.

The lower or inner end of the barrel 9 carries a depending shank 22 which is slightly less than semi-circular in cross section. The lower end of the shank 22 has an integrally formed head 23 thereon which provides an under-cut shoulder 24. The casing 1 is provided with an aperture 25 punched therethru which is of substantially the same shape as a plan of the head 23 so that said head and shank can be passed therethru when turned to a certain position, but which cannot be removed therefrom after being inserted therein and then turned to another position, the under cut shoulder 24 of the head 23 engaging the under surface of the casing 1 and preventing such removal.

10 The head end 5 of the handle 6 is provided with a finger 26 housed within the casing and which is adapted to retract a bolt 27 mounted to slide axially thru the casing 1. The bolt 27 has one end thereof of rectangular 25 cross section and an aperture 28 extends therethru for receiving the tip end of the finger 26.

The upper surface of the bolt adjacent the aperture 28 is notched out as shown at 29 for 30 a depth sufficient to permit retraction of the bolt without contacting with the end of the finger 26. The outer end of the rectangular portion of the bolt 27 has a roller 30 journaled therein in the usual manner for cooperating with a catch 31 rigidly mounted by screws or the like 32 to the door frame 33 of the article to which it is applied.

The opposite end of the bolt 27 is in the form of a round shank 34 which has a stiff 35 helical compression spring 35 wound therearound. One end of the compression spring 35 bears against the inner side of the casing 1 and the other end thereof bears against the 40 rectangular portion of the bolt 27 as shown 45 most clearly in Figs. 2 and 4.

Means are provided for preventing the retraction of the bolt 27 when the locking barrel has been turned so as to engage the shoulder 24 of the head 23 with the casing 1. Said means comprises a pawl 36 in a form 50 of a bell crank pivoted at 37 on the under side of the casing 1. The other arm 38 of the bell crank extends out and is positioned closely adjacent to the head 23 and is normally urged to the position shown in Fig. 2 55 by a helical compression spring 39. When the head 23 has rotated a half revolution from the position shown in Fig. 2 it bears against the arm 38 and swings the bell 60 crank on its pivot 37 so as to shift the pawl 36 toward the bolt 27 and swing the end of the pawl back of the shoulder 40.

In the operation of this latch when in an unlocked condition the handle 6 is grasped and raised upwardly causing the finger 26 65 to bear against the rear side of the aperture 28 and shift the bolt 27 against the action of the spring 35, which is to the right as viewed in Fig. 4 of the drawings. Upon release of the handle 6 the spring 35 returns 70 the bolt 27 to its normal locking position. If the door of the article to which this device is attached is slammed shut without regard to the handle 6 being raised, the bolt 27 is pushed to a retracted position by 75 the roller 30 contacting with the inclined face of the catch 31 in the usual manner. Such retraction of the bolt however does not operate the handle 6 on account of the slot 29 in which the end of the finger 26 slides. 80

When it is desired to lock this device the key 19 is inserted into the slot 13 of the barrel 9 and pushed inwardly a sufficient distance to move the protruding ends of the locking pin 14 out of their respective notches 17, at the same time bringing the notches 21 in the opposite sides of the key 19 into registry with the inturned flange 11 of the sleeve 10, thereby permitting the key 19 to be rotated relatively thereto. Rotation of 105 the key 19 a half revolution, rotates the barrel a half revolution thereby causing the undercut shoulder 24 of the head 23 to engage the underside of the marginal edge of the opening 25 in casing 1. Such rotation of the head also causes the arm 38 of the bell crank pawl 36 to be cammed on its pivot 37 a sufficient distance to move the pawl 36 back 110 of the shoulder 40 thereby locking the bolt 27 against retraction.

Although but one specific embodiment of this invention has been herein shown and described, it will be understood that numerous details of the construction shown may be altered or omitted without departing from 115 the spirit of this invention as defined by the following claims.

I claim:

1. A device of the class described comprising a casing, a bolt axially slidable on 120

said casing, a handle pivoted on said casing for operating said bolt, locking mechanism for preventing the operation of said handle, and a pawl actuated by said locking mechanism for engaging said bolt to prevent the sliding movement thereof.

2. A device of the class described comprising a casing, a bolt axially slidable on said casing, a shoulder on said bolt, a handle pivoted on said casing for retracting said bolt, locking mechanism for securing said handle to said casing to prevent pivotal movement thereof, and a pawl actuated by said locking mechanism to engage said shoulder for preventing the retraction of said bolt when said handle is locked to said casing.

3. A device of the class described comprising a casing, a bolt axially slidable on said casing, a shoulder on said bolt, a handle pivoted on said casing for retracting said bolt, locking mechanism mounted on said handle for securing said handle to said casing to prevent pivotal movement thereof, and a pawl actuated by said locking mechanism to engage said shoulder for preventing the retraction of said bolt when said handle is locked to said casing.

4. A device of the class described comprising a casing, a bolt axially slidable on said casing, yielding means for normally urging said bolt to one position, a handle for retracting said bolt, a lock for securing said handle in inoperative position, and a pawl actuated by said lock for preventing the re-

tracting of said bolt when said handle is locked in inoperative position.

5. A locking mechanism of the class described comprising a barrel having a transverse slot therethru, a transversely disposed pin slidable in said slot axially of said barrel, the opposite ends of said pin protruding beyond the sides of said barrel, a collar surrounding the outer end of said barrel, the inner end of said collar having diametrically opposed notches for receiving the protruding ends of said pin, a compression spring bearing against said pin for normally urging said pin toward said collar, said barrel having an annular opening 40 around the inner end of said collar for permitting said barrel to be rotated on its axis relative to said collar when said pin is out of engagement with said notches.

6. A device of the class described comprising a casing, a bolt axially slidable on said casing, yielding means for normally urging said bolt to one position, a handle pivoted on said casing, a finger on said handle for engaging and retracting said bolt 55 against the action of said yielding means, said bolt having an aperture therethru for receiving the end of said finger and a slot communicating with said aperture for permitting the end of said finger to slide there- 60 in without moving said handle.

In testimony whereof I have hereunto set my hand at Grand Rapids, Michigan, this 14th day of June, 1928.

ANDREW EKMAN.
